COMPOSITE BEAM STRUCTURE

Clemens Paul Cueni, Arlington, N. J., assignor to
 Porete Manufacturing Company, North Arlington, N. J., a corporation of New Jersey

Application July 2, 1941, Serial No. 400,851

9 Claims. (Cl. 72—71)

This invention is directed to composite structures wherein combined steel and concrete members are designed to carry predetermined loads.

Structures of this type have been known and used for a long time, including such composite structures in which a series of steel beams, suitably supported by pillars or other permanent members, carry a reinforced concrete slab in which metallic members, such as cleats, prongs, rods, and elements of various shapes, are attached to or in contact with such steel beams so that the concrete slab is securely anchored to the steel beams to form the desired composite structure. In all of the composite structures without temporary supports heretofore used, the steel beams were always designed to carry the entire dead load, which usually consists of the weight of the steel beams plus the weight of the concrete slab united therewith.

The additional strength present in the composite structure becomes available for the carrying of live loads only after the concrete slab has set. The steel beams were designed to carry their own weight and that of the concrete slab during the pouring and setting period, unless temporary intermediate supports were provided. However, such temporary supports added considerably to the expense of the construction, in that it required considerable labor for the erection, materials to be used therein, and a considerable amount of labor for the removal of such temporary supports. Continuous supports for the full length of the beams are impractical and in most cases far too expensive. Therefore, the temporary supports are usually spaced far apart and initial tensile stresses occur in the bottom of the steel sections between the supports. Furthermore, such supports were not completely effective, so that the initial stresses in the steel beams were almost as high where supports were used as where such supports were omitted.

The steel beams in carrying this dead load will have the greatest fiber stress in the extreme portion of the top and bottom. This extreme fiber stress is normally much below the allowable stress, which is usually 18,000 lbs. per square inch. The difference, 18,000 minus the extreme fiber stresses, is available to the composite section to carry the additional dead load and the live load. For instance, if the steel section is stressed by its own weight and the dead load of the concrete slab to say 5000 lbs. per square inch, there will be available for the composite section 18,000 minus 5000 equals 13,000 lbs. per square inch. This 13,000 lbs. can take care of the tensile stress pro-

duced by the live load acting on the composite section.

In such prior structures it was assumed that the steel section alone carried the dead load and the composite section the live load only. The stresses in the steel due to the dead load applied on the steel section plus the stresses in the steel due to the live load, applied on the composite section, therefore, did not exceed the allowable stress in the steel. The allowable stresses were usually arrived at by dividing the ultimate strength by an ample factor of safety. For instance, for concrete the ultimate strength at 28 days was divided by 2.5 to 4, and for structural steel the yield point was divided by about 2. It was generally regarded as essential to sound engineering that the initial stresses in the steel due to the dead load should be taken into consideration in designing any composite section.

20 It is among the objects of the present invention to provide a new and useful design of composite structures involving the use of steel beams and concrete members united therewith in which the design for a specific load is derived by the use of factors not heretofore known in the art.

25 It is among the objects of the present invention to provide a structure of steel and concrete wherein for a predetermined load, the steel area or the weight of the required steel is reduced substantially without impairing the carrying capacity of the composite section and with a reduction in the weight of the complete structure.

30 35 It has now been determined by theoretical investigation and by tests that a well designed composite section may be so computed as to reduce the area and, therefore, the weight of the steel section by a substantial amount without reducing the normal factor of safety. Actually the factor of safety is still higher than for conventional designs.

The present invention is based upon the discovery that in two similar composite sections, one without and the other with temporary intermediate supports during pouring and setting of the concrete, at the moment of failure, ultimate stresses are reached simultaneously in steel and concrete, and about at the same load, in both sections, despite the initial stresses due to the dead load in the section without temporary supports.

40 45 50 55 This behavior may partly be explained by the fact that the stress-strain diagram of the steel is not exactly the same as that of the concrete. It is no longer a straight line from the moment the steel is stressed to the elastic limit. The deviation from the straight line increases until, at

the moment the yield point in the steel is reached, deformations increase without an increase in stress. The stress-strain diagram of the concrete also shows a deviation from the straight line, from the moment the yield point is reached in the concrete, but by far not as pronounced as it is for steel, and there is never an increase in deformation without an increase in stress.

The stresses in the steel due to the dead load remain there, but the concrete takes more stresses from the live load and between the reaching of the elastic limit in the steel and the ultimate failure, the concrete, proportionately, takes so much more of the live load stresses that at the moment of failure the stresses are distributed in steel and concrete as if the concrete had participated in carrying the dead load. In other words, shortly before failure the stress distribution is the same as in a composite section, where the steel beam is temporarily supported during pouring and setting of the concrete, and in which steel and concrete participate in carrying the dead load as soon as the temporary supports are removed. Therefore, in the design of any composite section which has an effective shear reinforcement, it is safe to assume that the composite section carries both the dead and live load, and to disregard all initial stresses in the steel which may be produced by the dead load due to no temporary supports or due to supports which are not effective. However, enough concrete area must be provided so that the concrete is able to take care of additional stresses for an amount equal to that required by the dead load if it were acting on the composite section.

In previous designs, certain well established formulas have been used. For instance, in computing the tensile stress in the steel, the following formula had been used:

$$f_s = \frac{M_{D.L.}}{S_s} + \frac{M_{L.L.}}{S_s} \quad (No. 1)$$

In said formula, the reference character f_s represents the unit tensile stress in the extreme fiber of the steel. $M_{D.L.}$ represents the moment due to the dead load. $M_{L.L.}$ represents the moment due to the live load. S_s represents the section modulus of the steel section alone, and S_c represents the section modulus of the steel section of the composite section. The term "dead load" as used herein includes the weight of the beam plus the first pour of concrete. The term "live load" as used herein includes the second pour of concrete, such as for example in a bridge, a wearing surface, concrete railings, additional road bed, and the like. The live load also includes the additional dead load such as paving blocks, pipes, floor fill, and the like. In addition, the term includes the normal live load, namely, the temporary loading of the structure due to traffic and the like.

According to the prior art, the formula used for computing the compressive stress of the concrete of a composite section without temporary supports was as follows:

$$f_c = \frac{M_{L.L.}}{S_c} \quad (No. 2)$$

In this formula f_c represents the unit compressive stress in the extreme fiber of the concrete, and S_c represents the section modulus of the concrete in compression of the composite section.

These formulas were used in prior designs for computing the elements of the composite sections where no temporary supports were used in the construction of the structure in question.

According to the present invention, a different system of computation is used which is based upon the theory that the composite section carries the total load and there are disregarded any initial stresses in the steel due to the dead load where ineffective or no temporary supports are used. In computing the tensile stress in the steel, the following formula is used in accordance with the present invention:

$$f_s = \frac{M_{D.L.} + M_{L.L.}}{S_s} \quad (No. 3)$$

Comparing this formula with Formula No. 1 previously used, it will be seen that the section modulus of the steel section itself is not taken into consideration. The fiber stress in the steel section is computed entirely upon the section modulus of steel of the composite section. Thereby, the previously used formula has been modified and to some extent simplified.

The stress in the concrete according to the present invention is based upon the following formula:

$$f_c = \frac{M_{D.L.} + M_{L.L.}}{S_c} \quad (No. 4)$$

Comparing this formula with the previously used Formula No. 2, it will be seen that in computing the stress in the concrete, consideration has been given to the dead load which had previously been ignored in prior formulas for computing the stresses in the concrete.

In the accompanying drawing, constituting a part hereof, and in which like reference characters indicate like parts,

Fig. 1, *a* and *b*, are stress-strain diagrams of steel and concrete, *c* the diagram of deformation of a composite section;

Fig. 2, *a*, is a cross-sectional view of a composite beam, *b*; *c*, *d* and *e* are stress diagrams of that beam for different loads;

Fig. 3 is a cross-sectional view of a composite beam with no concrete cast about the steel section;

Fig. 4 is a cross-sectional view of a composite beam in which the steel section is entirely embedded in the concrete;

Fig. 5 is a cross-sectional view of a composite beam with no concrete cast about the steel section; and

Fig. 6 is a longitudinal view showing a composite beam suitably supported on permanent supports subjected to a live load.

In Fig. 1a is shown the stress-strain or stress-deformation diagram of steel and concrete. The stress-strain curve for steel 1 shows the deformation per unit, indicated at the bottom of the diagram, for any stress in the steel per unit indicated at left. The stress-strain curve for concrete 2 also is shown. In order to make easier a comparison of the two curves the scale of the ordinates (unit stress) for concrete is n times that for steel, n being the ratio of the modulus of elasticity of steel to that of concrete

$$\left(\frac{E_s}{E_c} \right)$$

E_s is generally assumed to be 30,000,000 lbs. per square inch. For this particular demonstration the E_c is assumed to be 4,545,000 lbs. per square inch, which determines $n=6.6$ and which corresponds to an average concrete for floors in bridges or high class buildings with an ultimate strength of about 4500 lbs. per square inch. On the similarity of these two curves are based the

design formulas generally used for reinforced concrete and also for composite sections of steel and concrete. If the two curves were not similar, the assumption that increments of a load applied consecutively to a reinforced concrete beam increase the stress in the steel and in the concrete in a certain ratio and for each increment for the same amount would be false. However, there is one difference between the two curves. As pointed out before, both curves deviate from a straight line from the moment the yield point is reached in the respective material. The deviation of the concrete curve is gradual, the curve has no abrupt changes. The deviation of the steel curve, starting after the stresses reach the elastic limit, increases rapidly until the yield point is reached. Then an abrupt change takes place. To effect an increase in deformation, an increase in stress was required until the yield point was reached, but now deformation increases without an increase in stress or even with a reduction in stress, as is shown by the downward direction of the steel curve at this point. This dissimilarity in the two curves is of small importance in usual reinforced concrete or composite designs, but it may be of considerable importance in composite sections with pre-stresses in the steel, as will be explained later.

In Fig. 1b, the same two curves 1 and 2 are shown but in a different position to each other. It must be remembered that in a composite section, without temporary supports when the concrete starts to take compressive stresses, the steel already has stresses due to the pre-stresses produced by the dead load. The two curves, therefore, do not start on the same level. For the present demonstration it is assumed that the dead load produces pre-stresses of 9000 lbs. per square inch. The concrete curve then starts at the level 9000 of the steel curve. The actual conditions, however, are not yet correctly represented. It is common practice to use a much higher factor of safety for the concrete than for the steel. 2 to 2.5 is normal for steel but 2.5 is the minimum for concrete and 3 to 4 may be an average for bridge decks and 2.5 to 3.5 an average for floors in buildings. Assuming the yield point of the steel is 39,600 lbs. per square inch, and the allowable stress 18,000 lbs. per square inch, then the factor of safety for the steel is 2.2. Assuming the ultimate strength of the concrete is 4000 lbs. per square inch and the allowable stress 1000 lbs. per square inch the factor of safety for concrete is 4. For steel the determining factor for ultimate strength in a composite structure is the yield point, for concrete it is the ultimate compressive strength. This difference is due to the above-mentioned difference in the two stress-strain curves. If a load is applied, producing a stress in the steel of 4500 lbs. per square inch, it is 25% of the allowable steel stress and 11.36% of the ultimate strength (yield point). According to the reinforced concrete theory the same load increases the stress in the concrete by 25% of the allowable stress that is by 250 lbs. per square inch. The increase in per cent of the ultimate stress of concrete, however, is only 6.25%, or 45% less (11.36 - 6.25 = 5.11). In other words, the deformation in the steel produced by a certain load has to be compared with the deformation produced in the concrete by a load about 45% lower. In this way curve 3 is determined as shown in Fig. 1b.

As long as the curves 3 and 1 are identical

or practically so, the stresses in steel and concrete will remain at the same ratio. If a load produces comparatively more deformation in the steel than in the concrete, then the concrete will take more stresses than assumed in the design. A comparison of curve 3 with curve 1 shows that this actually happens and at an increasing rate as the load increases. Once the stresses in the steel approach the yield point, the discrepancy between the two curves is considerable, and the concrete will take considerably higher stresses as assumed in the design.

A further explanation of this is given in Fig. 1c. In conventional reinforced concrete or composite design, it is assumed that for a certain increment of load there is always a corresponding increase in elongation in the steel and a corresponding increase in contraction in the concrete. The line 4-4' represents the zero line, showing a state of no load and therefore no deformation. A first increment of a load which will produce deformations is represented by the line 5-5' intersecting the line 4-4' at point 5° indicating the neutral axis of the composite section. If another increment of load is applied producing comparatively a greater deformation in the steel than in the concrete as shown by the line 6-6', the neutral axis moves up to point 6°. A moving up of the neutral axis means a comparatively higher stress in the concrete and a comparatively lower stress in the steel. If an elongation in the steel occurs without an increase in stress, as shown by the line 7-7', the neutral axis as shown by intersection point 7° still moves up. As the concrete cannot contract without an additional force, that means that it takes additional stresses even though the stresses in the steel do not increase. Exactly that happens when the stresses in the steel reach the yield point.

Fig. 2a is a cross section of a composite beam with concrete cast about the steel section. The steel section 8 may be a rolled I beam or wide flange section, or a built up riveted or welded section, the top flange may be identical to the bottom flange or smaller, and a cover plate may be attached to the bottom flange to increase the steel area. Steel section 8 is permanently supported at the ends but has no intermediate temporary supports. Attached to the upper part of the steel section may be a shear reinforcement 9 in form of a spiral or other to insure an effective bond between steel and concrete. A concrete haunch 10 is cast about the steel section, to protect the steel or increase the bond, supported entirely by the steel section, as is also concrete slab 11 poured monolithically with the concrete haunch 10. The concrete slab 11 may have cross reinforcement bars in top and bottom 12 and longitudinal reinforcing bars 13 top and bottom.

Fig. 2b shows the stress diagram of the steel section under the dead load, the arrows 14 representing the tensile stresses in the bottom and 15 the compressive stresses in top of the beam, 16 being the center of gravity of the steel section.

Fig. 2c shows the stress diagram of the composite section under live load. At a first increment of load the stress distribution may be rectilinear, as indicated by the line 17-18 the intersection with the zero line being at point 19, through which the neutral axis 20 of the composite section passes. A further increment of load will produce stresses indicated by the line

21—22, which is no longer a straight line. The neutral axis may move up from 23 to 24.

Fig. 2d shows the combination of the shear diagram Figs. 2b and 2c, the horizontal arrows 24 represent the tensile stresses in the steel at the bottom of the steel section. The arrows 25 at the top of the steel section show the remaining compressive stresses in the steel due to the dead load. The horizontal arrows 26 represent the compressive stresses in the concrete. The stress distribution is no longer rectilinear as seen by comparing it with the dotted line 27—28.

Fig. 2e shows the stress diagram of the composite section at the moment failure starts, in other words, at the moment the stresses in the steel reach the yield point. The horizontal arrows 29 represent the yield point stresses f_y in the steel, the arrows 30 the ultimate compressive stresses f'_c in the concrete. This stress diagram is identical with that of a similar composite section without initial stresses in the steel. If the stress distribution was not already balanced before the yield point in the steel was reached, it certainly will be balanced as soon as the steel begins to yield and elongation in the steel increases without an increase in stress.

The diagrams in Figs. 1 and 2 prove conclusively what has been verified by tests:

1. That in a composite beam in which the dead load, due to the omission of intermediate temporary supports, produces initial stresses in the steel, the live load produces comparatively higher stresses in the concrete than it does in a similar composite section which has intermediate temporary supports. The concrete sustains a greater proportion of the live load stresses than is assumed in the standard design formulas.

2. That due to different factors of safety applied to concrete and steel, the concrete sustains a greater part of the stresses in any composite section than is assumed in the standard design formulas.

3. That due to the difference between the stress-strain curve of the steel and that of the concrete in a composite section, wherein the yield point of the steel is the determining factor for ultimate strength, there occurs a redistribution of the stresses between steel and concrete in favor of the steel, so that the concrete, at the moment failure starts, sustains considerably greater stresses than assumed in the design.

Since the concrete, partly due to the initial stresses in the steel, sustains higher stresses from the live load than assumed in the standard design formulas and since concrete and steel in a composite section, at the moment of ultimate load are stressed according to the actual ratio of their modulus of elasticity and the actual location of the neutral axis, it follows that any initial stress due to the dead load in the steel section of a composite beam may be disregarded in the design of said composite beam.

The dead load stresses remain in the steel section, but before the ultimate load is reached the distribution of the stresses in such a composite beam is exactly the same as in a similar composite beam with effective intermediate temporary supports. Both beams, therefore, have the same factor of safety. This holds true for all conditions and regardless of whether the neutral axis of the composite beam is outside or inside the steel section, provided however that the concrete area and the shear reinforcement are designed to take care of all stresses due to dead and live load.

The magnitude of the initial stresses is of no

importance. With greater initial unit stresses the balance of the stresses will take place faster than with smaller ones.

Fig. 3 shows a cross-section of a composite beam without concrete cast around the steel section. The steel section 31 permanently supported at both ends carries its own weight and the reinforced concrete slab 32 cast on top of it. Shear reinforcement 33 in the form of an angle or other, is welded or otherwise attached to the steel beam. The concrete slab 32 may have cross reinforcement 34 on top or bottom, or both. The neutral axis of the composite section 35 is above the steel beam.

Fig. 4 shows a cross-section of a rectangular composite beam. The steel section 36 permanently supported at both ends carries its own weight and the concrete 37 cast about it. The concrete may have the form as indicated by line 38 or as indicated by line 39. The neutral axis of the composite section 36 passes through the steel beam. To increase the bond between concrete and steel and insure the transmission of the horizontal shear, wire mesh or reinforcing bars 39 may be placed around the beam, attached or not, to the steel section.

Fig. 5 shows another cross-section of a composite beam. The steel section 40, the area of which is increased by attaching a cover plate 41 to the bottom flange, carries its own weight and the concrete slab 42 poured on top of it. The neutral axis of the composite section 40 is outside the concrete slab and passes through the steel section.

Fig. 6 shows the combination of the composite section with its permanent supporting members. Composite section 43 is supported at its ends by pillars or the like 44 and 45 respectively. The live load, which the composite section is designed to carry in addition to the dead load, is represented by the vertical arrows 46. Unless the steel section is cambered to offset the deflection due to the dead load the composite section will show a dead load deflection indicated by the broken line 47. In addition to that the live load applied on the composite section causes a deflection shown by the broken line 48.

To show the saving obtained by the use of the present invention, one may compare the design with that obtained by using the prior formulas. In so doing, according to the present formula, one assumes that the dead and live loads are carried by the composite section, regardless of the initial stresses in the steel produced by the dead load. In calculating the design according to the previously used formulas, there is taken into consideration the initial stresses in the steel due to the dead load. That is, it is assumed that the steel alone carries the dead load and that the composite section carries the live load only.

Example 1

Assume that a highway bridge is to be constructed, with stringer sections having a span of 75 feet, spaced 6 feet from center to center and having a concrete slab 7.5 inches thick. The bridge is to resist a bending moment as follows:

$$\begin{aligned} M.D.L. &= 7,750,000 \text{ inch pounds} \\ M.L.L. &= 8,030,000 \text{ inch pounds} \end{aligned}$$

The allowable extreme fiber stress for the steel is 18,000 pounds per square inch and the allowable fiber stress for the concrete is 1000 pounds per square inch.

According to the design of the present invention, the required steel section is a 36 inch wide

flange section having a weight of 194 pounds per lineal foot. The section moduli of steel and concrete of the composite section are:

$$S_c = 18,300 \text{ in.}^3 \quad S_s = 876 \text{ in.}^3$$

The extreme fiber stresses in concrete and steel are:

Concrete, due to $D.L. + L.L. f_s =$

$$\frac{7,750,000 + 8,030,000}{18300} = 860 \text{ lbs. per sq. in.}$$

Steel, due to $D.L. + L.L. f_s =$

$$\frac{7,750,000 + 8,030,000}{876} = 18000 \text{ lbs. per sq. in.}$$

The design according to the prior formulas requires a 36 inch wide flange section having a weight of 230 pounds per lineal foot. The section moduli for the steel section and the composite section are:

$$S' = 835.5 \text{ in.}^3 \quad S_c = 20,000 \text{ in.}^3 \quad S_s = 1051 \text{ in.}^3$$

The extreme fiber stresses in steel and concrete are:

Concrete, due to $L.L. f_s =$

$$\frac{8,030,000}{20,000} = 401.5 \text{ lbs. per sq. in.}$$

Steel, due to $D.L. f_s' =$

$$\frac{8,053,750}{835.5} = 9640 \text{ lbs. per sq. in.}$$

$$\text{Due to } L.L. f_s = \frac{8,030,000}{1051} = 7650 \text{ lbs. per sq. in.}$$

$$f_s \text{ total} = 17290 \text{ lbs. per sq. in.}$$

(The increase in dead load moment is due to the 36 lbs. more weight of the steel section, 230-194 lbs.)

As a result, the two bridges so designed are comparable in weight carrying capacity with a saving in steel by the present design as follows:

36 WF 230 total weight=75×230#=17,250 lbs.
36 WF 194 total weight=75×194#=14,550 lbs.

$$\text{Saving per beam}=2700 \text{ lbs.}$$

The concrete slab is the same and the shear spiral about the same for both sections. The concrete slab is the same for both designs because its dimensions are determined by other considerations. Its purpose is to provide a bridge floor or a floor slab in buildings, and to transmit upon the stringers or floor beams the loads applied between them. For designs made in accordance with the present invention additional concrete area will exceptionally be required.

Example 2

A highway bridge is constructed of stringer sections having a span of 40 feet spaced six feet from center to center. It has a concrete slab 7.5 inches thick, and is to resist the following bending moment:

$$M_{D.L.} = 1,960,000 \text{ inch pounds}$$

$$M_{L.L.} = 2,340,000 \text{ inch pounds}$$

The allowable extreme fiber stress for the steel is 18,000 pounds per square inch, and for the concrete 1000 pounds per square inch.

A design made in accordance with the present invention has a required steel section having a 16 inch wide flange section with a weight of 88 pounds per lineal foot. The section moduli of steel and concrete of the composite section are:

$$S_c = 5570 \text{ in.}^3 \quad S_s = 239 \text{ in.}^3$$

The extreme fiber stresses in concrete and steel are:

Concrete, due to $D.L. + L.L. f_s =$

$$\frac{1,960,000 + 2,340,000}{5570} = 772 \text{ lbs. per sq. in.}$$

Steel, due to $D.L. + L.L. f_s =$

$$\frac{1,960,000 + 2,340,000}{239} = 18,000 \text{ lbs. per sq. in.}$$

In a construction in accordance with the prior art, the required steel section is a 16 inch wide flange section having a weight of 114 pounds per lineal foot. The section moduli for the steel section and the composite section are:

$$S' = 197.4 \text{ in.}^3 \quad S_c = 6250 \text{ in.}^3 \quad S_s = 305 \text{ in.}^3$$

The extreme fiber stresses in steel and concrete are:

Composite sections without temporary supports.

Composite sections without temporary supports.

Concrete, due to $L.L. f_s =$

$$\frac{2,340,000}{6250} = 375 \text{ lbs. per sq. in.}$$

Steel, due to $D.L. f_s =$

$$\frac{2,022,400}{197.4} = 10,200 \text{ lbs. per sq. in.}$$

(the increase in dead load moment is due to the 26 lbs. more weight of the steel section 114-88 lbs.)

$$\text{Due to } L.L. f_s = \frac{2,340,000}{305} = 7680 \text{ lbs. per sq. in.}$$

$$\text{Total } f_s = 17,880 \text{ lbs. per sq. in.}$$

The saving in steel by the present invention as compared with the prior art is as follows:

$$16 \text{ WF } 114 \text{ total weight} = 40 \times 114\# = 4560 \text{ lbs.}$$

$$16 \text{ WF } 88 \text{ total weight} = 40 \times 88\# = 3520 \text{ lbs.}$$

$$\text{Saving per beam}=1040 \text{ lbs.}$$

The concrete slab is the same and the shear spiral about the same for both sections.

In Example 1 the saving in the weight of the steel in favor of the new design amounts to 15.65%; in Example 2 to 22.8%. The saving in cost, in per cent of the cost of the steel sections, is about the same, and the actual saving per beam, assuming a cost of five cents per pound of steel at bridge site is \$135.00 for Example 1, and \$52.00 for Example 2.

There are various advantages inherent in the present invention, as for instance in the new system the steel section does not have to be designed to carry alone all the dead load but it can be assumed that said load is distributed over the entire deep section of the composite beam. It is unnecessary to use intermediate temporary supports under the beam during the pouring and setting of the concrete. This is of great advantage, as it increases the speed with which the structure may be erected and it decreases the cost thereof substantially. Often temporary supports are undesirable or sometimes impossible.

The saving in the amount of steel not only effects a saving in cost, but it results in making the complete structure lighter and results in a saving in cost of girders, columns, foundations and the like.

A composite beam, built according to the invention, has less deflection after the concrete has set than a similar beam temporarily supported during pouring and setting of the concrete. The

working stresses of the concrete at the design loads are lower in an unsupported beam than in a temporarily supported one, as there are, in the first one, no stresses or only small ones due to the dead load. It is a well known fact that the plastic flow of concrete increases with the increase of the permanent compressive stress. Therefore, the plastic flow of the concrete in a temporarily supported beam must be greater than in an unsupported beam. Plastic flow may not have great influence on the ultimate strength of a composite beam, but it certainly increases deflection.

In the above description the invention has been applied to structures wherein steel beams were incorporated. The invention is not limited thereto but wood beams are equally adaptable and the same principles apply in such cases also. Of course, the numerical values of the factors involved are different. The term "steel" as used in the claims appended hereto is, therefore, intended to include wood beams also.

Reference is here made to my copending application Serial No. 402,618, filed July 16, 1941, and entitled "Prestressed composite structure," the description of which is made a part hereof.

What I claim is:

1. A composite steel-concrete structure comprising a steel beam, permanent supports on which said beam is mounted, a concrete slab cast on said steel beam, connected thereto by a shear reinforcement, said beam being deflected intermediate the ends thereof by the dead load of said concrete having been applied without temporary intermediate supports, said structure being designed to carry a predetermined dead and live load, the area of the steel section being computed on the basis that the initial stresses therein produced by the dead load are disregarded and that the composite steel-concrete section carries both the dead and live load, the area of the concrete and the shear reinforcement being sufficient to withstand the stresses due to the dead and live loads.

2. A composite steel-concrete structure comprising a steel beam, permanent supports on which said beam is mounted, said beam being unsupported at the intermediate portions, a concrete slab cast on said steel beam, connected thereto by a shear reinforcement, said beam being deflected intermediate the ends thereof by the dead load of said concrete having been applied without temporary intermediate supports, said structure being designed to carry a predetermined dead and live load, the area of the steel section being computed on the basis that the initial stresses therein produced by the dead load are disregarded, the unit tensile stress in the extreme fiber of the steel being based on the formula

$$\frac{M_{D.L.} + M_{L.L.}}{S_s}$$

wherein $M_{D.L.}$ is the moment due to the dead load, $M_{L.L.}$ is the moment due to the live load, and S_s is the section modulus of the steel section of the composite section, the area of the concrete and the shear reinforcement being sufficient to withstand the stresses due to the dead and live loads.

3. A composite steel-concrete structure comprising a steel beam, permanent supports on which said beam is mounted, said beam being unsupported at the intermediate portions, a concrete slab cast on said steel beam, connected thereto by a shear reinforcement, said beam being

deflected intermediate the ends thereof by the dead load of said concrete having been applied without temporary intermediate supports, said structure being designed to carry a predetermined dead and live load, the area of the steel section being computed on the basis that the initial stresses therein produced by the dead load are disregarded, the unit compressive stress in the extreme fiber of the concrete being based on the formula

$$\frac{M_{D.L.} + M_{L.L.}}{S_s}$$

wherein $M_{D.L.}$ is the moment due to the dead load, $M_{L.L.}$ is the moment due to the live load, and S_s is the section modulus of the concrete in compression of the composite section, the area of the concrete and the shear reinforcement being sufficient to withstand the stresses due to the dead and live loads.

4. The method of making a composite steel-concrete structure designed to carry a predetermined live and dead load which comprises computing the area of the steel section on the basis that the initial stresses therein produced by the dead load are disregarded, supporting said steel section on permanent supports without temporary intermediate supports, pouring concrete on said beam without the presence of temporary intermediate supports, and allowing said concrete to set.

5. The method of making a composite steel-concrete structure designed to carry a predetermined live and dead load which comprises computing the area of the steel section on the basis that the initial stresses therein produced by the dead load are disregarded, the unit tensile stress in the extreme fiber of the steel being based on the formula

$$\frac{M_{D.L.} + M_{L.L.}}{S_s}$$

wherein $M_{D.L.}$ is the moment due to the dead load, $M_{L.L.}$ is the moment due to the live load, and S_s is the section modulus of the steel section of the composite section, supporting said steel section on permanent supports without temporary intermediate supports, pouring concrete on said beam without the presence of temporary intermediate supports, and allowing said concrete to set.

6. The method of making a composite steel-concrete structure designed to carry a predetermined live and dead load which comprises computing the size of the steel section on the basis that the initial stresses therein produced by the dead load are disregarded, supporting said steel section on permanent supports without temporary intermediate supports computing the area of the concrete section on the basis that the composite steel-concrete section carries both the dead and live load, pouring concrete on said beam without the presence of temporary intermediate supports, and allowing said concrete to set.

7. The method of making a composite steel-concrete structure designed to carry a predetermined live and dead load which comprises computing the area of the steel section on the basis that the initial stresses therein produced by the dead load are disregarded, the unit tensile stress in the extreme fiber of the concrete being based on the formula

$$\frac{M_{D.L.} + M_{L.L.}}{S_s}$$

wherein $M_{D.L.}$ is the moment due to the dead load, $M_{L.L.}$ is the moment due to the live load, and S_c is the section modulus of the concrete in compression of the composite section, supporting said steel section on permanent supports without temporary intermediate supports, pouring concrete on said beam without the presence of temporary intermediate supports, and allowing said concrete to set.

8. A composite steel-concrete structure comprising a steel beam, permanent supports on which said beam is mounted, said beam being unsupported at the intermediate portions, concrete cast about said beam to provide a unitary structure, said beam being deflected intermediate the ends thereof by the dead load of said concrete having been applied without temporary intermediate supports, said structure being designed to carry a predetermined dead and live load, the area of the steel section being computed on the basis that the initial stresses therein produced by the dead load are disregarded and that the composite steel-concrete section carries both the dead and live load, the area of the concrete and the shear reinforcement being sufficient to withstand the stresses due to the dead and live loads.

9. A composite steel-concrete structure comprising a steel beam, permanent supports on which said beam is mounted, said beam being unsupported at the intermediate portions, concrete cast about said beam to provide a unitary structure, said beam being deflected intermediate the ends thereof by the dead load of said concrete having been applied without temporary intermediate supports, said structure being designed to carry a predetermined dead and live load, the area of the steel section being computed on the basis that the initial stresses therein produced by the dead load are disregarded, the unit tensile stress in the extreme fiber of the steel being based on the formula

$$\frac{M_{D.L.} + M_{L.L.}}{S_c}$$

wherein $M_{D.L.}$ is the moment due to the dead load, $M_{L.L.}$ is the moment due to the live load, and S_c is the section modulus of the steel section of the composite section, the area of the concrete and the shear reinforcement being sufficient to withstand the stresses due to the dead and live loads.

CLEMENS PAUL CUENI.
